JOHN R. CAMERON, OF PITTSBURG, PENNSYLVANIA.

Letters Patent No. 70,800, dated November 12, 1867.

IMPROVEMENT IN AIR ENGINES.

The Schedule referred to in these Letters Patent and making part of the same.

TO ALL WHOM IT MAY CONCERN:

Be it known that I, JOHN R. CAMERON, of Pittsburg, in the county of Allegheny, and State of Pennsylvania, have invented a new and improved Vacuum Air Engine; and I do hereby declare that the following is a full, clear, and exact description thereof.

The object of this invention is to form a vacuum by the expansion of air by heat, and by other appliances, by which the piston of a working cylinder may be driven by the simple pressure of the atmosphere, and power obtained thereby for driving machinery or other purposes; and the invention consists principally in providing a vacuum-chamber and bellows, a movable fire-box, a hot-air chamber, a water-cistern, and pump, which, in addition to suitable valves, pipes, rods, and water-cocks, &c., accomplish the object I have in view.

To enable those skilled in the art to make and use my invention, I will proceed to describe its construction and operation, reference being had to the accompanying drawings, and to the letters of reference marked theron, in which—

Figure 1 represents a vertical sectional elevation, and

Figure 2 a sectional horizontal view through the hot-air chamber.

Similar letters indicate like parts in the drawings.

A represents the vacuum-chamber; B, the fire-box, and d the blast pipe in the fire-box. C is the hot-air chamber; D, the bellows-head; E, the water-cistern or reservoir. F represents the pump; G, the valve sliding on the bottom of the hot-air chamber C. H is the rod to the valve G; I is the bed-plate or base, upon which the apparatus rests; and J represents the rods, which support the hot-air chamber and water-cistern.

These rods pass up through the bed-plate I, and through the bottom plate of the hot-air chamber C, having shoulders near their upper ends, upon which the hot-air chamber rests, and to which it is fastened by screw-nuts.

The vacuum-chamber A is raised from the bed-plate sufficiently high to allow pipes to be attached to the bottom, from the pump, and also from the working cylinder. These pipes are indicated by the letters b and i.

There is a thin lining, b', inside the vacuum-chamber and the outside covering, with a water space between, indicated by the letter a. This water-space is in communication with the water-cistern E. The bellows D operate inside of the lining and water-space, being surrounded by the lining, and may be of any suitable construction, the head D' working loosely, and being supported by a spiral spring, e, by which it is elevated, and which also elevates the fire-box when the apparatus is in operation, as hereafter described.

There is an aperture through the top of the bellows-head at e, with a valve opening upwards, through which air is forced into the fire by the action of the bellows. This valve is represented as closed in the drawing.

The fire-box or furnace B is a short section of a cylinder, with a grated bottom, as seen at g, on which the fire rests, and under which there is an ash-pit, g'.

The blast pipe d is firmly attached to the fire-box, the lower end extending down below the ash-pit, the end closing over the valve and aperture in the top of the bellows-head when in operation, and receiving the discharged air therefrom. There are holes through the sides of this pipe, (that is the portion of it which passes through the fire,) and through which the air is discharged into the fire. At the top of this pipe the rod f is attached, from which the fire-box is suspended, and by which it is operated.

The hot-air chamber C is a square box resting upon the rods J. It has an inner lining of thin metal, which is so placed that a water-space, a', is left between this lining and outside case. This water-space is in communication with the water pipes m and n, which supply and discharge the water therefrom.

Through the bottom of this hot-air-chamber there is an aperture larger in diameter than the fire-box B, a space, o, being left around the fire-box, sufficient for the escape of air from the vacuum-chamber into the hot-air chamber. There is a door in the side of this hot-air chamber for the introduction of fuel to the furnace, and a tube, P, set upon its top, with a valve in it, which opens and closes when necessary. The smoke, gases, and heated air escape from the hot-air chamber through this tube. The valve G slides on the bottom of the hot-air chamber, and is operated by the rod H. It is secured to its place by the pieces p p, which are grooved on the lower side, and being firmly fastened to the bottom of the chamber the valve works in these grooves, and is secured and guided thereby in its motion back and forth. The office of the valve is to close the aperture through the bottom of the chamber C. The water-cistern E supplies the water to the water-space around the

vacuum-chamber A through the pipe S; the water being let on and shut off by the valves v , on the bottom of the rod T, inside the cistern E.

The water is supplied to the cistern through the pipe S'. The pump F is used to withdraw the water from around the vacuum-chamber through the pipe i.

The rod T works air-tight through the top of the water-cistern, and the rods f and H, as well as T, work through stuffing-boxes, as seen at x. The water-spaces around the vacuum-chamber and hot-air chamber are for the purpose of partially condensing the air and products of combustion, and also to prevent over-heating.

The fire-box, valves, and other working parts of my apparatus are worked and operated by the usual mechanical means.

This vacuum engine being intended to produce a vacuum merely for a working cylinder, it is not deemed necessary to describe that cylinder, it being constructed in the usual manner with ports, piston, valves, &c.

The operation is as follows: The fire-box B descends from the position represented in the drawing, down into the vacuum-chamber, forcing down the bellows. The air in the vacuum-chamber becomes greatly rarefied and escapes upward. A portion escapes through the top of the bellows, and is discharged into the fire through the blast pipe d, and a portion escapes around the fire-box, through the space o, into the hot-air chamber above. The fire-box is immediately raised into the hot-air chamber, and the valve G is quickly closed over the aperture, leaving a vacuum in the vacuum-chamber. Into this chamber the working cylinder is exhausted through the pipe b, and the atmospheric pressure upon the opposite side of the piston in that cylinder furnishes the power which I obtain.

This operation is repeated at every stroke of the piston. The valve G is withdrawn, the fire-box descends, and another vacuum is formed as before, and the working cylinder is exhausted from the other end, and so on at each revolution.

I do not broadly claim the forming of a vacuum by rarefying the air, or otherwise, to receive the exhaust of a working cylinder; but what I do claim as new, and desire to secure by Letters Patent, is—

1. The combination of the vacuum-chamber A and the hot-air chamber C, when constructed and arranged as described.

2. I claim the fire-box B, with its blast pipe d, and the water-cistern E, in combination with the vacuum-chamber A, constructed and operating substantially as herein set forth.

3. I also claim the inner lining b', for the purpose of forming more rapidly a vacuum in A, and also the bellows D, in combination with the vacuum-chamber A, substantially as herein described, for the purposes specified.

J. R. CAMERON.
